UNITED STATES PATENT OFFICE

106,050

DESIGN FOR A CASKET TRIMMING OR ANALOGOUS ARTICLE

Raymond Larson, Chicago, Ill., assignor to Central Metallic Casket Co., Chicago, Ill., a corporation of Illinois

Substituted for (abandoned) application Serial No. D-58,185, August 17, 1935. This application February 12, 1937, Serial No. D-67,671

Term of patent 14 years

To all whom it may concern:

Be it known that I, Raymond Larson, a citizen of the United States, residing at 2207 North Lamon Avenue, Chicago, in the county of Cook and State of Illinois, have invented a new, original, and ornamental Design for a Casket Trimming or Analogous Article, of which the following is a specification, reference being had to the accompanying drawing, forming part thereof:

Fig. 1 is a top plan view of the casket trimming showing my new design.

Fig. 2 is a fragmentary top plan view on an

enlarged scale, showing approximately a quarter section of Fig. 1, and

Fig. 3 is a fragmentary side elevational view thereof.

This case is a substitute for applicant's prior application filed August 17, 1935, Serial No. D-58,185.

I claim:

The ornamental design for a casket trimming or analogous article, as shown.

RAYMOND LARSON.
